UNITED STATES PATENT OFFICE

2,537,500

EAR CLIP

Sandor Alexander Wittmayer, New York, N. Y.

Application January 26, 1946, Serial No. 643,593

5 Claims. (CL 63—14)

1

This invention relates to clips by which ornaments are secured on the ears, as worn by women, and has for its main object to provide a device of this type which will be more reliable than ear clips used or proposed heretofore.

Another object of the invention is to provide ear clips, or ear ornament securing means, which will be more attractive in appearance than those used at present.

Still further objects of my invention will be partly apparent and partly pointed out as the specification of the same progresses.

In the drawings, forming a part of this specification and accompanying the same:

Fig. 1 is a partly sectional side elevational view of my novel ear clip; the spaces in some parts being shown somewhat exaggeratedly, for the sake of clearness;

Fig. 2 is an end view thereof as indicated by the arrow 2 in Fig. 1, being on a smaller scale;

Fig. 3 is a fragmentary sectional view, the section being taken on the line 3—3 in Fig. 1, and

Fig. 4 shows a cross section of the inner clip member, as indicated by 4—4 in Fig. 1.

Referring now to the drawings more in detail, by characters of reference, the numeral 10 indicates my novel ear clip, in general, being mainly composed of two elements, a relatively stationary U-shaped clip member 11 and a movable member 12.

The ear lobe of the person is indicated by dotted lines 13, and it will be seen that upon using my device the outer branch 14 of the U-shaped element 11 will be placed against the outer surface 15 of the ear lobe 13, said U-shaped element encircling the lower end of the ear lobe, as indicated in Fig. 1, and its inner branch 16 being to the rear thereof.

The desired ear ornament or jewelry proper will be secured on the outer branch 14, as usual. (Not shown.)

A tube 17 is secured to the rear of the movable clip member 12, said tube having a longitudinal slot 18 in which the upper end 19 of the inner branch 16 may slide. Said top 19 carries a sleeve nut 20 in which rotates a comparatively thin screw pin 21. The forward end 22 of the screw pin is rotatable in the clamping piece 12, but is not allowed to axially move with reference thereto, in a word, the forward end of the screw pin 21 is swiveled in the clamp or clip member 12. One form of such swivelled engagement is indicated in Fig. 1, but such devices are well known in this art and a more detailed description thereof is not necessary.

2

The rear end of the screw pin 21 carries a preferably knurled operating disc 23, which may have depending flange 24 to better steady the same on the tube 17.

5 The use and operation of my device will be understood from the drawings and herein description, but I may offer the following further explanations.

The ear clip having been placed over the lower

10 portion of the ear lobe as indicated in Fig. 1, but in a loose manner, the disc 23 will be rotated in the right direction, whereby screw 21 will cause the U-shaped element 11 to move rearwardly, as indicated by the arrow 25. This movement will 15 press the forward branch 14 thereof against the ear lobe and such operation will be continued until the device is safely secured on the ear lobe by the clamping action of the opposing members 14 and 12, as will be understood.

20 When it is desired to remove the ornament from the ear lobe, disc 23 will be rotated in the opposite direction. U-shaped member 11 now moving forwardly and its front branch 14 releasing the ear lobe.

25 It will be seen that I provided a novel ear clip which while very simple in construction still is reliable in its clamping action and easily tightened or loosened and in which the moving parts are securely guided. Such moving parts, at the 30 same time, are concealed and the device has an attractive, esthetic appearance.

What I claim is new and want to protect by Letters Patent of the United States, is:

1. In an earclip, the combination of a U-shaped member of generally uniform small cross section, having inner and outer legs of greater length than their distance from one another, a screw threaded sleeve nut of small cross section on said inner leg, a thin screw passing through said nut, a clamping plate swivelled at the outer end of said screw whereby said screw may rotate in said plate but may not move in an axial direction with respect thereto, a thin tube secured on said clamping plate and extending over said screw, and an operating disk fixed on the inner end of said screw and closing the inner end of said tube, said tube having a longitudinal slot in which the inner leg of said U-shaped member may slide, and said clamping plate being substantially wider than the diameter of said tube.
2. In a device, as set forth in claim 1, the inner leg of said U-shaped member being oval and narrowed in the direction transversely to said tube, whereby the slot in said tube may be made smaller.

3. In a device, as set forth in claim 1, the engagement of said screw with said plate being provided by a sleeve member secured at the inner end of said screw and rotatable in said plate, and means on said sleeve preventing an axial movement thereof with reference to said plate.

4. In an earclip, the combination of a U-shaped member of generally uniform small cross section, having inner and outer legs of greater length than their distance from one another, a screw threaded sleeve nut of small cross section on said inner leg, a thin screw passing through said nut, a clamping plate swivelled at the outer end of said screw whereby said screw may rotate in said plate but may not move in an axial direction with respect thereto, a thin tube secured on said clamping plate and extending over said screw, and an operating disk fixed on the inner end of said screw and closing the inner end of said tube, said tube having a longitudinal slot in which the inner leg of said U-shaped member may slide, and said clamping plate being substantially wider than the diameter of said tube, a flange on said operating disk slidably engaging the rear end of said tube.

5. In an earclip, the combination of a U-shaped member of generally uniform small cross section, having inner and outer legs of greater length

than their distance from one another, a screw threaded sleeve nut of small cross section on said inner leg, a thin screw passing through said nut, a clamping plate swivelled at the outer end of said screw whereby said screw may rotate in said plate but may not move in an axial direction with respect thereto, a thin tube secured on said clamping plate and extending over said screw, and an operating disk fixed on the inner end of said screw and closing the inner end of said tube, said tube having a longitudinal slot in which the inner leg of said U-shaped member may slide, and said clamping plate being substantially wider than the diameter of said tube, said clamping plate being curved to follow the curvature of the rear lower portion of an ear lobe.

SANDOR ALEXANDER WITTMAYER.
